DOFFING AND DONNING APPARATUS

James H. Daughdrill, Dalton, and Robert F. Jes-
sen, La Grange, Ga., assignors to Callaway
Mills, La Grange, Ga., a corporation of Georgia

Application April 30, 1946, Serial No. 666,138

20 Claims. (Cl. 57—53)

1

This invention relates to apparatus for use in performing doffing and donning operations in connection with textile machines provided with spindles on which cores, such as bobbins, cops, spools, etc., are mounted for rotation, so that yarn may be wound thereon. More particularly, the invention is concerned with a novel apparatus by the use of which full cores may be removed from the spindles of such a machine and empty cores may be mounted on the spindles, the new apparatus being of simple, inexpensive construction and easy to operate, so that it can be employed efficiently by an operator who does not possess a high degree of manual dexterity. The new apparatus may be utilized for doffing and donning textile machines of various kinds, as, for example, spinning frames, quillers, etc., but, since it may be employed to special advantage in connection with spinning frames, a form of the apparatus suitable for such use will be illustrated and described in detail for purposes of explanation.

Heretofore, the operations of doffing and donning the bobbins of spinning frames have been commonly performed by hand, and, since the frames are idle during the periods when those operations are going on, it is important that a doffer should be highly skilled and able to work rapidly and efficiently, so that the inevitable loss of production will be kept as low as possible. As skilled doffers are not always available, the desirability of developing an apparatus by which doffing and donning could be carried on by an unskilled operator has long been recognized and some attempts have been made to devise such apparatus. However, either because of the complexity of the proposed apparatus or for other reasons, the previous efforts to solve the problem have met with little or no success and, so far as we are aware, no doffing and donning equipment has been employed to any considerable extent in this country up to the present.

The apparatus of the invention is manually operated and it may be constructed to operate on any number of spindles from a single spindle up to the total on an entire side of a frame. The apparatus includes a carriage which is mounted for movement vertically and also horizontally in a direction transverse to the row of spindles on the machine. Also, in one form of the apparatus, the carriage is movable lengthwise of the row of spindles and, for this purpose, it may be suspended from a track mounted permanently above the level of the operator's head at the front of the machine but is preferably mounted on a

truck that can be moved along the machine. The carriage is provided with means by which one or more full cores on the spindles can be gripped upon lowering of the carriage and can be removed when the carriage is raised. The carriage also carries means for supporting one or more empty cones in such relative positions that by lowering the carriage, such empty cores can be mounted on the spindles. The new machine includes numerous other features to be described later, which facilitate its use.

For a better understanding of the invention, reference may be had to the accompanying drawings, in which

15 Fig. 1 is a view in front elevation and with parts broken away of one form of apparatus constructed in accordance with the invention;

Fig. 2 is a sectional view on the line 2—2 of Fig. 1;

20 Fig. 3 is a fragmentary rear elevational view, with parts broken away, of the apparatus shown in Fig. 1, but on a larger scale;

Fig. 4 is a sectional view on the line 4—4 of Fig. 3;

25 Figs. 5 and 6 are views similar to Fig. 4 showing different stages in the operation of the apparatus;

Fig. 7 is a fragmentary elevational view of the carriage of the apparatus;

Fig. 8 is a sectional view on the line 8—8 of Fig. 7; and

Fig. 9 is a sectional view on the line 9—9 of Fig. 7.

The apparatus shown in the drawings is of the portable type and is constructed for doffing and donning a plurality of spindles in each cycle of operation. The apparatus comprises a carriage 10 which, in the form shown, is a box-like structure, which may be made of light sheet metal and comprises a bottom wall 11, a top wall 12, and walls 13. The walls are secured together in any convenient manner, as, for example, edge portions 11a and 12a of walls 11 and 12 may be folded to lie against the inner face of one wall 13 and be secured thereto, while the opposite edges of walls 11 and 12 abut the inner face of the other wall 13 and are secured thereto by angle members 14 lying within the structure and secured to the abutting walls.

The walls 13 extend upwardly from the bottom wall 11 substantially beyond the top wall 12 and a plurality of spring clips 15 arranged in upper and lower rows are secured to the outer face of each wall 13. These clips are for holding empty bobbins 16 in vertical parallel relation, and stepped stops 17 may be mounted on the under surfaces

of outward flanges 13a on walls 13 above the clips. The stops are so formed and mounted that, when bobbins are placed in a row of clips with their upper ends against the stops or the under surface of the flange 13a, successive bobbins in the row lie at different levels and the bobbins form three series with the bobbins in each series separated by a pair of bobbins, one in each of the other two series.

Aligned openings 18 are formed in the upper and lower walls 11, 12, respectively, of the carriage and these openings are large enough to permit a full bobbin to be passed therethrough. The removal of the full bobbins from the spindles is effected by means of a pair of gripping bars 19, which are carried by arms 20a, 20b suspended on pivot pins 21 carried by fittings 22 attached to the lower surface of the bottom wall 11 of the carriage in spaced relation. The bars 19 are urged toward each other by springs 23 connecting each pair of arms 20a, 20b and the bars may be spread apart against the action of the springs sufficiently to permit the yarn masses on full bobbins on the spindles of the spinning frame to pass between the bars. The springs then move the bars inwardly beneath the yarn masses on the bobbins to grip the bobbins.

The carriage 10 is mounted for movement along the frame and may also be moved vertically and toward and away from the frame. In the construction shown, the carriage is rigidly mounted between the legs of a U-shaped member 24, the cross bar of which is provided with a plurality of eyes 24a to which are attached the lower ends of the springs 25. The upper ends of the springs are attached to one part of a swivel member 26, the other part of which is attached to one leg of a U-shaped hanger 27. The other leg of the hanger carries a roller 28 movable along a track 29. With the arrangement described, the spring mounting for the carriage permits the carriage to be moved up and down and toward and away from the spinning frame and also to be rotated about the vertical axis of the swivel member, so that one or the other of the sides of the carriage may face the frame. The track 29 may be permanently installed in front of and above the level of the frame, or, as in the construction disclosed, the track may be carried on a bracket 30 attached to a standard 31 mounted in a wheeled truck 32. The track projects beyond the standard 31 at both sides of the latter, so that a portion of the track overlies the truck and another portion extends beyond the end of the truck.

A magazine 33 for empty bobbins is mounted above the top of the body of the truck on members 34 and the magazine is made of front and rear walls and end walls and is open at the top and bottom. U-shaped vertical guides 35 made of sheet metal are mounted in opposed relation on the inner faces of its front and rear walls and the lower ends 36 of the side walls of the guides are turned inwardly toward one another to form spring fingers. The front and rear walls of the magazine are spaced a distance slightly greater than the length of a bobbin 16 so that a stack of bobbins lying horizontally one above the other may be mounted in each pair of aligned guides and be supported on the spring fingers 36 at the lower ends of the guides. The lowermost bobbin in each stack can then be readily moved downwardly from between the guides and past the fingers, while the other bobbins in each stack are left behind. To facilitate removal of the bobbins from the magazine by means to be de-

scribed, the rear wall of the magazine is cut away as indicated at 37 to expose the bores in the lowermost bobbins in the stacks.

The transfer of the bobbins from the magazine to the carriage is performed by means of a U-shaped frame 38, the legs of which are pivotally mounted on brackets 39 attached to the front wall of the magazine. The cross bar 38a of the frame is formed with a plurality of openings on a uniform spacing and stepped stops 40, similar to stops 17, are mounted on the upper face of the cross bar, each stop having a pair of openings extending through its portions of different height and aligned with openings through the cross bar. The stops are so spaced along the cross bar, that there is a portion of the bar containing one opening between the ends of adjacent stops. A bar 41 is mounted on frame 38 outside of cross bar 38a and extends parallel to the latter. The bar 41 is slightly longer than the cross bar and, at its ends, it is provided with rods 42 which extend parallel to the legs of the frame and lie outside the latter. The rods 42 pass through guides 43 on the legs of the frame and the bar 41 may be moved toward and away from cross bar 38a with its movement limited by collars 44 mounted on rods 42 and lying between guides 43. The bar 41 is provided with a pair of latch members 45 pivotally mounted thereon and having hooked ends engageable with pins 46 projecting from the rear face of cross bar 38a and bar 41 carries a plurality of pins 47 entering the openings through the cross bar. When bar 41 is moved close to the cross bar and the latch members 45 are engaged with their pins 46, the pins 47 on bar 41 project beyond the inner face of the cross bar for substantially their entire length. When the latch members 45 are unhooked from their pins, bar 41 may be moved away from the cross bar, so that the ends of pins 47 lie flush with the inner face of the cross bar.

The frame 38 may be swung from a vertical position to the horizontal position shown in dotted lines in Fig. 4, provided bar 41 is unlatched from cross bar 38a and withdrawn as far as possible therefrom. When the frame is in the horizontal position shown in Fig. 4, the ends of pins 47 lie aligned with the bores through the lowermost bobbins in the magazine and by moving bar 41 toward the cross bar, the pins 47 may be introduced into the bores in the bobbins. When bar 41 has thus been moved toward cross bar 38a and has been locked in position relative thereto by the latch members 45, frame 38 may be swung downwardly to its vertical position and, in this movement of the frame, the pins 47 will remove the lowermost bobbins from the stacks in the magazine.

In the use of the apparatus described, the magazine is charged with empty bobbins and the clips on both faces of the carriage are filled with empty bobbins by means of the transfer frame 38 and its associated parts in preliminary operations. In such use of the transfer frame, it is swung to horizontal position as above described and bar 41 is moved toward the magazine so that empty bobbins are picked up on the pins 47, after which bar 41 is latched in position. The transfer frame is then swung back to the vertical position and held in place by a brace 48, which is hinged to the rear face of bar 41 and is formed with a notch in its free end, so that it may be seated on the top of the rear wall of the truck. The carriage is then moved downwardly and to-

ward the transfer frame, and the legs of the frame are provided with guide members 49, which may be engaged with similar members 50 at the ends of the carriage, to hold the carriage and frame in proper relation as the carriage is moved toward the frame. As the carriage approaches the frame, the clips on the rear face of the carriage are forced past empty bobbins on the pins 47 on the frame and, when the bobbins are properly seated, the bar 41 is unlatched from cross bar 38a and allowed to fall, so that the pins are withdrawn from the bobbins. The carriage may then be swung away from the frame and the charging of the clips on one face of the carriage is completed. The carriage is next turned end for end and the operations are repeated to fill the clips on the other face of the carriage.

When doffing of the textile machine is required, the machine is stopped, its rail is lowered, and the yarn ends are slackened off in the usual way. The truck is then moved to one end of the machine and the carriage is moved to the end of its track beyond the end of the truck and lowered by the attendant over a group of spindles at the end of the machine. In this downward movement of the carriage, the ends of the full bobbins on the spindles pass between the bars 19 on the carriage and the bobbins enter the aligned openings 18 in the upper and lower walls of the carriage. The bars 19 are sprung apart by engagement of the yarn masses on the bobbins with the bars, and when these masses have passed beyond the bars, the latter swing in toward the bobbins. Upon raising of the carriage, bars 19 remove the full bobbins from the spindles. The carriage is next moved away from the machine slightly to bring the empty bobbins 16 in clips 15 on the rear face of the carriage in alignment with the spindles. Upon the lowering of the carriage, the empty bobbins are placed upon the spindles and the carriage is then moved horizontally away from the spindles to free the bobbins on the spindles from the clips. The attendant next moves the carriage along its track to a position over the truck and spreads bars 19 apart to let the full bobbins supported on the bars drop into the body of the truck.

The clips 15 on a vertical wall of the carriage are spaced more closely than the spacing between spindles on the machine and, in the donning apparatus described, the spacing between adjacent bobbins held by the clips is one-third the spacing between adjacent spindles. Accordingly, in each donning operation, one-third of the empty bobbins are removed from the clips and, when the carriage is fully charged, it carries a sufficient number of empty bobbins for six of the donning operations described. The carriage may be made in sufficient length, so that when fully loaded, it will hold enough empty bobbins for the entire machine. Accordingly, the carriage need not be charged with bobbins during the doffing and donning operation, but the transfer of bobbins from the magazine to the carriage may be effected while the machine is running.

In the foregoing, the new apparatus has been described in a form suitable for use with a spinning frame, but it will be apparent, that it may be employed with obvious alterations for use in doffing and donning any textile machine containing a single row of spindles. The term "yarn" as used herein is, accordingly, to be understood as applicable to various textile strands including yarn:

We claim:

1. A doffing and donning apparatus for use with a textile machine having a spindle adapted to rotate a core mounted thereon to wind yarn on the core, which comprises a carriage mounted for vertical and horizontal movement, means on the carriage for supporting an empty core in vertical position, and means on the carriage for engaging a full core on the spindle and removing the full core from the spindle upon upward movement of the carriage.

2. A doffing and donning apparatus for use with a textile machine having a row of spindles adapted to rotate cores mounted thereon to wind yarn on the cores, which comprises a carriage mounted for vertical and horizontal movement, means on the carriage for supporting a plurality of empty cores in parallel vertical arrangement, the cores in the supporting means being spaced a distance equal to the spacing between adjacent spindles on the machine, and means on the carriage for engaging a plurality of full cores on the spindles and removing the full cores from the spindles upon upward movement of the carriage.

3. A doffing and donning apparatus for use with a textile machine having a spindle adapted to rotate a core mounted thereon to wind yarn on the core, which comprises a carriage, means for supporting the carriage for vertical and horizontal movement, means on the carriage for supporting an empty core in vertical position, and means on the carriage for removing a full core from the spindle upon upward movement of the carriage, said removing means including members engageable with the yarn mass on the full core from beneath.

4. A doffing and donning apparatus for use with a textile machine having a spindle adapted to rotate a core mounted thereon to wind yarn on the core, which comprises a carriage, means for supporting the carriage for vertical and horizontal movement, means on the carriage for supporting an empty core in vertical position, means on the carriage for engaging a full core on the spindle and removing the full core from the spindle upon upward movement of the carriage, and means on the carriage above the core engaging and removing means for supporting the full core removed from the spindle.

5. A doffing and donning apparatus for use with a textile machine having a spindle adapted to rotate a core mounted thereon to wind yarn on the core, which comprises a carriage mounted for vertical and horizontal movement, the carriage having top and bottom walls with aligned openings, means on the carriage for supporting an empty core in vertical position, and means on the carriage below the bottom wall for engaging a full core on the spindle, when the latter lies within the openings, and removing the full core from the spindle upon upward movement of the carriage.

6. A doffing and donning apparatus for use with a textile machine having a spindle adapted to rotate a core mounted thereon to wind yarn on the core, which comprises a carriage mounted for vertical and horizontal movement, means on the carriage for supporting an empty core in vertical position, and means on the carriage for engaging a full core on the spindle and removing the full core from the spindle upon upward movement of the carriage, said engaging and removing means including a pair of parallel bars mounted for movement toward and away from one another and biased toward one another.

7. A doffing and donning apparatus for use with

a textile machine having a row of spindles adapted to rotate cores mounted thereon to wind yarn on the cores, which comprises a magazine for storing empty cores side by side, a carriage mounted for vertical and horizontal movement, means for holding the magazine and carriage in fixed relation, means on the carriage for supporting a plurality of empty cores in parallel vertical arrangement, means operable to remove a plurality of cores from the magazine and transfer them to the supporting means on the carriage, and means on the carriage for engaging a plurality of full cores on the spindles and removing the full cores from the spindles upon upward movement of the carriage.

8. A doffing and donning apparatus for use with a textile machine having a row of spindles adapted to rotate cores mounted thereon to wind yarn on the cores, which comprises a magazine for storing empty cores side by side, a carriage mounted for vertical and horizontal movement, means for holding the magazine and carriage in fixed relation, means on the carriage for supporting a plurality of empty cores in parallel vertical arrangement, means mounted adjacent the magazine and operable to remove a plurality of cores from the magazine and transfer them to the supporting means on the carriage, and means on the carriage for engaging a plurality of full cores on the spindles and removing the full cores from the spindles upon upward movement of the carriage.

9. A doffing and donning apparatus for use with a textile machine having a row of spindles adapted to rotate cores mounted thereon to wind yarn on the cores, which comprises a magazine for storing empty cores side by side, a carriage mounted for vertical and horizontal movement, means for holding the magazine and carriage in fixed relation, means on the carriage for supporting a plurality of empty cores in parallel vertical arrangement, a member mounted adjacent the magazine and provided with means for engaging a plurality of empty cores in the magazine, the member being movable to transfer the cores from the magazine to the supporting means on the carriage, and means on the carriage for engaging a plurality of full cores on the spindles and removing the full cores from the spindles upon upward movement of the carriage.

10. A doffing and donning apparatus for use with a textile machine having a row of spindles adapted to rotate cores mounted thereon to wind yarn on the cores, which comprises a carriage mounted in front of the machine for movement lengthwise of the machine, vertically, and toward and away from the machine, supporting means on the carriage for holding a plurality of empty cores in parallel vertical arrangement, the cores being held in a plurality of series with the cores in each series spaced a distance equal to the spacing of the spindles and the cores in each series having their lower ends in a horizontal plane offset from the plane in which the lower ends of the cores in any other series lie, and means on the carriage for engaging a plurality of full cores on the spindles and removing the full cores from the spindles upon upward movement of the carriage.

11. A doffing and donning apparatus for use with a textile machine having a row of spindles adapted to rotate cores mounted thereon to wind yarn on the cores, which comprises a track disposed in front of the machine and above the level of the spindles, a carriage, means, movable along the track, from which the carriage is suspended for vertical and horizontal movement,

means on the carriage for supporting a plurality of empty cores in parallel vertical arrangement, and means on the carriage for engaging a plurality of full cores on the spindles and removing the full cores from the spindles upon upward movement of the carriage.

12. A doffing and donning apparatus for use with a textile machine having a row of spindles adapted to rotate cores mounted thereon to wind yarn on the cores, which comprises a truck movable along the front of the machine, a carriage mounted on the truck for vertical and horizontal movement, means on the carriage for supporting a plurality of empty cores in parallel vertical alignment, and means on the carriage for engaging a plurality of full cores on the spindles and removing the full cores from the spindles upon upward movement of the carriage.

13. A doffing and donning apparatus for use with a textile machine having a row of spindles adapted to rotate cores mounted thereon to wind yarn on the cores, which comprises a truck movable along the front of the machine, a carriage mounted on the truck for vertical and horizontal movement, means on the carriage for supporting a plurality of empty cores in parallel vertical alignment, means for engaging a plurality of full cores on the spindles and removing the full cores from the spindles upon upward movement of the carriage, a magazine for empty cores mounted on the truck, and means on the truck for withdrawing a group of cores from the magazine and transferring them to the supporting means on the carriage.

14. A doffing and donning apparatus for use with a textile machine having a row of spindles adapted to rotate cores mounted thereon to wind yarn on the cores, which comprises a truck movable along the front of the machine, a standard mounted on the truck, a track mounted on the standard, a carriage suspended from the track and movable vertically and also along and transversely of the track, means on the carriage for supporting a plurality of empty cores in parallel vertical arrangement, and means on the carriage for engaging a plurality of full cores on the spindles and removing the full cores from the spindles upon vertical movement of the carriage.

15. In a doffing and donning apparatus for use with a textile machine having a spindle adapted to rotate a core mounted thereon to wind yarn on the core, a carriage provided with a support adapted to hold an empty core in vertical position, and a pair of parallel bars mounted on the carriage to swing on horizontal pivots, the bars being biased toward one another and being separable to receive between them a full core on the spindle.

16. In a doffing and donning apparatus for use with a textile machine having a spindle adapted to rotate a core mounted thereon to wind yarn on the core, a carriage mounted for vertical and horizontal movement, means on the carriage for supporting an empty core in vertical position, means on the carriage for engaging a full core on the spindle and removing the full core from the spindle upon upward movement of the carriage, and means on the carriage for receiving the full core on the spindle and supporting it after its removal from the spindle.

17. In a doffing and donning apparatus for use with a textile machine having a spindle adapted to rotate a core mounted thereon to wind yarn on the core, a carriage mounted for vertical and horizontal movement, the carriage having ver-

tically aligned openings large enough to receive a full core, means on the carriage for supporting an empty core in vertical position, and means on the carriage beneath said openings for engaging a full core on the spindle, when the full core lies within the openings, and removing the full core from the spindle upon upward movement of the carriage.

18. In a doffing and donning apparatus for use with a textile machine having a spindle adapted to rotate a core mounted thereon to wind yarn on the core, a carriage mounted for vertical and horizontal movement, spaced means on the carriage for receiving and supporting a full core, means on the carriage below said spaced means for engaging a full core on the spindle, when the full core is received within said spaced means, and removing the full core from the spindle upon upward movement of the carriage, and means on the carriage for supporting an empty core in position to be mounted on the spindle upon downward movement of the carriage.

19. In a doffing and donning apparatus for use with a textile machine having a row of spindles adapted to rotate cores mounted thereon to wind

yarn on the cores, a carriage mounted for vertical and horizontal movement, means on the carriage for receiving and supporting a row of full cores, means on the carriage for engaging a plurality of full cores on the spindles, when the full cores are within said receiving and supporting means, and removing the full cores from the spindles upon upward movement of the carriage, and means on the carriage for supporting a row of empty cores in position to be mounted on the spindles upon downward movement of the carriage.

20. In a doffing and donning apparatus for use with a textile machine having a spindle adapted to rotate a core mounted thereon to wind yarn on the core, a carriage mounted for vertical movement, means on the carriage for engaging a full core on the spindle below the yarn mass on the core and removing the full core upon upward movement of the carriage, and means on the carriage above the core engaging and removing means for supporting the full core after its removal from the spindle.

JAMES H. DAUGHDRILL.
ROBERT F. JESSEN.
